SIGNALING

Application filed July 6, 1929, Serial No. 376,324, and in Germany July 20, 1928.

It is known that the suppression of the carrier-frequency in transmitters for wireless telephony has a number of advantages as compared with normal telephony with carrier-frequency. An important advantage is the saving of the energy otherwise radiated out with the carrier-frequency. However, the suppression of the carrier-frequency has considerable disadvantages also. These are: 10 a considerable complication of the sender as compared with the simple carrier-telephony; and, the fact that the transmission cannot be heard without suitable special receivers working with the addition of a carrier wave.

15 According to the invention, both disadvantages are eliminated, not by suppressing the amplitude of the carrier-frequency, but by reducing it to a small fraction of its normal value. With normal carrier telephony 20 and 100% modulation, the amplitude of the side band is one-quarter of the carrier amplitude. Since this value must only be reached for the peaks, to avoid over-modulation, one has worked so far with a mean degree 25 of modulation amounting to about 30%. In this case the side band amplitude amounts to $\frac{1}{6}$ of the carrier current amplitude; or in other words, the carrier-current is six times as strong as the side band amplitude.

30 According to the invention a reduction of the carrier current amplitude from that value to the order of magnitude of the mean carrier-frequency amplitude takes place. This can be accomplished most simply by 35 means at the transmitter, and the transmitted communication is very well heard even with simple receivers. The energy contained in the reduced carrier then amounts to only a few percent of the value with ordinary carrier telephony. Therefore, the 40 greater part of the energy radiated out with the carrier in normal carrier telephony can be saved by this simple method or else be used for the side bands.

45 All connections known for the suppression of the carrier are suitable for this method, for instance, the push-pull scheme shown in Fig. 1 of the accompanying diagram, and, the filter arrangement shown in Fig. 2 of the drawing.

In Fig. 1, two tubes, 1 and 2, work in phase opposition. Their grids are coupled by the coil 3, from there a branch leads over coil 4 to the minus pole of a grid bias battery 5, the positive pole of which is connected with the cathode of both tubes. The grid biasing battery 5 is chosen high enough so that one works at the knee of the anode characteristic. The anodes of both tubes are connected with a coil 6, the center branch of which is connected with the cathode over the anodic voltage supply 7.

High frequency energy is conveyed to the system through the input circuit 8; this causes a high frequency voltage at the winding 4 and therefore at both grids. Since this high frequency voltage is co-phasal on both grids, the effect of both anode currents, induced from the coil 6 in the output circuit 9, is neutralized. If modulation voltages 65 for example voice currents are fed to the system over the input circuit 10, the coil of which induces currents in the coil 3, both grids are influenced with low frequency in push-pull fashion and the equilibrium between the two tubes is disturbed. The side band frequencies thus produced are transferred to the output circuit 9.

The suppression of the carrier wave requires a far-going symmetry of the connections, equal position of the tube characteristics, etc., the construction of which is exceedingly difficult.

According to the invention the equilibrium of the system is disturbed additionally without considering small asymmetries, for example, by adding to the grid circuit a stopper circuit in tune with the high frequency fed at 8, which reduces the high frequency amplitude conveyed to this grid compared with the other. Thus the anodic alternating currents of tube 1 and tube 2 are different from each other. The current induced in the output circuit 9 is brought to about the same amplitude that the side bands have on the average. Since the equilibrium is purposely much disturbed, to obtain a carrier balance desirable for intelligibility, exact balancing of the tubes and good symmetry of the connections require no further attention.

To carry out the proposed procedure, the following method is also suitable. By means of the modulation voltage (voice currents for example) an auxiliary frequency is modulated first, with this the transmitter proper is modulated and the band-pass filters are thus arranged so that the carrier-frequency is separated out.

The filter chains necessary to separate the carrier from the side bands are constructed more simply, however, that is, with a smaller number of units. Here also the arrangement is much simpler than is necessary for complete suppression since much less is required from the filter chains and therefore the construction is simpler.

In carrying into practice this method of first modulating an auxiliary frequency with the modulator energy, recourse may be had to a circuit arrangement according to Figure 2. In a "composite" or "mixing" tube M1 the oscillations generated by the intermediate-frequency oscillator G1 are modulated by the speech currents generated by the microphone T. A filter arrangement F1 is provided to partly suppress the carrier wave.

The intermediate-frequency carrier wave serves for the modulation of the radio frequency oscillations generated by the generator G2 in another composite tube B2. The carrier wave of this generator as well as side-band energy are separated in another filter circuit F2.

Since the filter F1 may have also a certain permeability for the carrier wave, it need not, of course, comprise as many units or meshes as a filter serving the purpose to pass only side-band energy unobstructedly. Hence, the filter scheme required in connection with the present invention may consist of a lower number of units.

I claim as my invention:

1. In undulating electrical current apparatus the combination of a pair of electron discharge devices, means for coupling the anodes of the devices together, means for coupling the control electrodes of the devices together, means for polarizing the control electrodes of the devices to substantially the same potential value, means for supplying oscillatory energy to each of the control electrodes in parallel, and means comprising a tuned circuit in series with only one of the control electrodes and the polarizing means for preventing the equal application of oscillatory energy to the control electrodes of the devices.

2. In undulating electrical current apparatus the combination of a pair of electron discharge devices, means for coupling the anodes of the devices together, means for coupling the control electrodes of the devices together, means for polarizing the control electrodes of the devices to substantially the same potential value, means for supplying

oscillatory energy to each of the control electrodes in parallel, and means comprising a tuned circuit in series with only one of the control electrodes and the polarizing means for preventing the equal application of oscillatory energy to the control electrodes of the devices.

3. In undulating electrical current apparatus the combination of a pair of electron discharge devices, means for coupling the anodes of the devices together, means for coupling the control electrodes of the devices together, means for polarizing the control electrodes of the devices to substantially the same potential value, means for supplying oscillatory energy to each of the control electrodes in parallel, means comprising a tuned circuit in series with only one of the control electrodes and the polarizing means for preventing the equal application of oscillatory energy to the control electrodes of the devices, means for applying alternating energy to the control electrodes of the devices in series, means for amplifying the output of the devices, and means for electromagnetically transmitting the amplified output of the electron discharge devices.
